UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP.

SHEET-RETAINING POST FOR LOOSE-LEAF LEDGERS.

Application filed February 3, 1927. Serial No. 165,547.

This invention relates to certain improvements in sheet retaining posts for loose leaf ledgers, and has for its object to greatly facilitate the proper insertion and removal 5 of the post.

The sheets of loose leaf ledgers are frequently provided with open U-shaped gates at their margins which gates engage with the usual ledger posts thereby preventing 10 any lengthwise displacement of the sheets.

But the sheets are also perforated at a suitable locality which perforations align when the sheets are properly placed within the ledger, and a retaining post is then inserted 15 through one side of the ledger within these perforations the inner end of the post engaging within a suitable recess in the opposite face of the ledger, the object of this retaining post being to prevent the sheets 20 from getting accidentally displaced when the ledger is not in use.

Some loose leaf ledgers have a fixed capacity and therefore a solid post is used in this instance, while other ledgers are composed 25 of expansible sections, and accordingly an expansible telescoping spring-actuated post is employed.

The drawings illustrate this invention in connection with a spring-actuated telescoping post, but the invention is equally applicable to a solid post with no change whatever in adaptation.

In a ledger having expansible sections, when it is desired to close the ledger the sections are pressed together and locked as usual, and the resilient telescopic post is inserted through one side of the ledger into the perforations and engage with a suitable recess in the opposite side of the ledger and this post is pressed in firmly until its outer end is substantially flush with the side of the ledger, and a screw driver or coin is inserted within a slot at the end of the post and the latter is given a quarter turn so that 45 a pin extending laterally from the post will lock behind the metal side of the ledger.

These loose leaf sheets clamped within an expansible ledger are quite heavy in the aggregate, and since the perforations cut through the sheets are not always perfectly aligned, and for the further reason that the sheets may sag slightly in the direction of the length, it frequently happens that, when it is desired to open up the ledger, and a coin

or screw driver is placed within the slot at the end of the resilient post, the latter will not spring out owing to the friction against it of the sheets, and then the ledger must be agitated so as to shake the perforations loose from the post, but it has frequently happened that a post, stuck in this manner, has unexpectedly shot out and has caused painful damage to an operator, and it is the special object of this invention to prevent any such occurrence and to greatly facilitate the insertion and removal of the post.

In the accompanying drawing which forms a part of this application,

Figure 1 is a detail elevation of the resilient post, the outer or handle portion thereof being sectioned and broken away—

Figure 2 is an elevation of the post from a different viewpoint—

Figure 3 is an elevation of the post similar to Figure 1 but showing the handle portion swung at right angles—

Figure 4 is an end view of the construction shown at Figure 3—

Figure 5 is a sectional elevation of loose leaf expansible members showing the post inserted therein preparatory to locking, the end portions of these members being removed—

Figure 6 is a view similar to Figure 5 showing the post locked within the ledger members, and

Figure 7 is a broken side elevation showing the hinged and locking handle housed within the cheek piece of one of the ledger members.

Similar numerals of reference denote like parts in the several figures of the drawing.

A loose leaf ledger of the expansible nature is composed of the usual oval shaped metallic hollow cheek pieces 1 and 2, and telescoping sections 3 and 4 secured respectively to said cheek pieces.

The usual posts with which the sheets engage are omitted as they form no part of the present invention.

5, 6, are openings cut through the inner wall of the cheek piece 2 and the section 4, and 7, 8, are similar perforations cut through the inner wall of the cheek piece 1 and the section 3, these perforations being opposite each other.

In the outer wall of the cheek piece 1 is formed a longitudinal recess 9 whose inner

end leads into an opening 10 that is in alignment with the perforation above referred to, and it is through these perforations and this opening that the retaining post is inserted. 5 The retaining post which is illustrated is of the usual type comprising an inner member 11 and a telescoping outer member 12, the latter containing the usual coil spring which functions to normally extend these post 10 members.

13 is a handle whose inner end has bifurcations 15 which embrace an ear 16 formed on the end of the part 12, a pin 14 being driven through these bifurcations and ear 15 whereby the handle is pivoted to the post and is capable of being swung at right angles to the latter, and the pin 14 is prolonged so as to extend laterally from the inner end of the handle and form a locking stud 18. 20

20 The handle 13 has extending therethrough a longitudinal opening 19 within which is a coil spring 20 which bears against a ball 21 at the lower end of the handle and is tensioned by means of a screw 22 which bears 25 against this spring, and seats 23 and 24 are formed within the end of the ear 16 and one edge thereof so that the ball may engage within these seats and hold the handle respectively in straight and folded positions.

30 In applying this retaining post the latter is passed through the opening 10 and the perforations 5, 6, 7, and 8, until its abuts the outer wall of the cheek piece 2, and the handle is then grasped and pushed inwardly until the stud 18 has passed inside the wall of the cheek piece 1, whereupon the handle is given a quarter turn and released so that said stud will lock behind the inner wall of this cheek piece, and thereupon the 35 handle is folded inwardly within the recess 9 so as to be out of the way and not interfere with the manipulation of the ledger.

40 The outer portion of this recess is enlarged to form a finger opening 25, and in removing the post the operator inserts his finger within this opening and pulls the handle outwardly, then gives it a quarter turn and removes the retaining post.

45 While the form of recess shown is very 50 convenient any other suitable recess may be utilized in case it is desired to fold the handle out of the way and the invention is not limited in this respect.

55 In ledgers that have a fixed capacity a post of a fixed length is used, and it is merely necessary in such an instance to pivot the handle to the end of the post just as in the manner above described, the operation being precisely the same.

60 As a mere matter of convenience and economy in manufacture, the pivot pin 14 is prolonged at one end so as to extend laterally from one side of the handle, to form the locking stud, but it will be obvious that this

locking stud may project laterally from the member 12, since this member always rotates with the handle when the latter is turned to bring the stud into locking position, and therefore the invention is not limited in this respect. 65 70

What is claimed is:—

1. In a loose leaf ledger having side cheek pieces, a sheet retaining post having a handle pivoted thereto and provided with a laterally extending locking stud, said handle adapted to be turned whereby said stud will lock against its adjacent cheek piece and thereafter fold at right angles within a suitable housing. 75

2. In a loose leaf ledger, a sheet retaining post having at its outer end a hinged handle and provided with a locking stud, whereby after said post has been inserted within the ledger and sheets therein and turned to bring said stud into locking engagement with the ledger, said handle may be swung at right angles to the post. 80 85

3. A construction as in claim 1 with the addition that a recess is formed at the side of the ledger within which the handle may be swung so as to lie substantially flush with said ledger. 90

4. A construction as in claim 1 with the further proviso that the handle is hollow and contains a spring impelled ball which engages within seats formed in the post when the handle is opened or closed. 95

5. A sheet retaining post adapted to be inserted within the cheek pieces of a loose leaf ledger and having a handle hinged to its outer end and provided with a stud which engages one wall of the adjacent cheek piece to lock the post when the latter is positioned and the handle revolved, the latter being capable of being swung at a right angle to the post proper and housed substantially flush with the outer face of said adjacent cheek piece. 100 105

6. A construction as in claim 6 in which the handle resiliently seats against the post when alined with the latter or swung at a right angle thereto. 110

7. In a loose leaf ledger having side cheek pieces, a sheet retaining post structure comprising a rotary sheet retaining post proper and a handle hinged thereto, a locking stud extending laterally from said structure and adapted to engage one wall of the adjacent cheek piece when the structure is revolved and a recess formed within the side of said adjacent cheek piece, said handle adapted to be swung at a right angle to the post so as to lie substantially flush with said adjacent cheek piece after said stud has been engaged with said wall. 115 120 125

In testimony whereof I affix my signature hereto.

JOHN SCHADE

CERTIFICATE OF CORRECTION.

Patent No. 1,661,811.

Granted March 6, 1928, to

JOHN SCHADE.

It is hereby certified that error appears in the printed specification of the above numbered patent requiring correction as follows: Page 2, line 109, claim 6, for the words "A construction as in claim 6" read "A construction as in claim 5"; and that the said Letters Patent should be read with this correction therein that the same may conform to the record of the case in the Patent Office.

Signed and sealed this 17th day of April, A. D. 1928.
